UNITED STATES PATENT OFFICE.

WILLIAM H. BEEHLER, OF BALTIMORE, MARYLAND.

SUITCASE UMBRELLA-HOLDER.

1,233,019.

Specification of Letters Patent. Patented July 10, 1917.

Application filed November 3, 1915. Serial No. 59,391.

To all whom it may concern:

Be it known that I, WILLIAM HENRY BEEHLER, a citizen of the United States, residing at Baltimore, Maryland, have invented a certain new and useful Suitcase Umbrella-Holder, of which the following is a specification.

My invention relates to holding means co-operating with the parts of an ordinary 10 suit-case to hold therein in a convenient manner a foldable umbrella.

The invention is particularly adapted to coöperate with folding umbrellas of my own invention disclosed in certain patents and 15 pending applications but the features of the invention may be adapted in some cases to umbrellas of other construction.

The characteristics and advantages of the 20 invention are hereinafter pointed out sufficiently in connection with a detailed description of the accompanying drawing which shows one exemplifying embodiment of the invention.

This embodiment is the best that I have 25 up to the present time devised, but it is to be understood that the invention may be embodied in many different forms and I do not limit myself to details, except as claimed.

30 Figure 1 is a front view of a suit-case with the top raised showing the holding devices and umbrella in position within the top.

35 Fig. 2 is an enlarged detail in side elevation of one of the holders applied to one of the suit-case straps.

Fig. 2^a is an enlarged detail of part of a 40 detachable umbrella handle adapted to co-operate with the holding device.

Fig. 3 is a similar detail, but in top plan. Fig. 4 is a section on the line 4—4 of Fig. 2.

I prefer to construct folding umbrellas so 45 that the tip 1 is connected to the body portion 2 by a foldable linkage. In this way the tip may be unscrewed and folded alongside of the umbrella body in the position shown but is not usually completely detached therefrom. The handle 3, best shown 50 in Fig. 2^a, is provided with a dowel 5 to fit within the end of the umbrella rod and this dowel is provided with a spring-operated latch 6 to engage a slot in the rod to hold the handle in operative position. When the 55 umbrella is folded the handle is preferably removed entirely by depressing the spring-

latch 6. It is desirable to provide means for definitely locating the handle within the suit-case, and this location should be preferably alongside of the umbrella so that all 60 parts of the umbrella may be easily found and quickly put together when it is wanted for use.

The umbrella is of such dimensions that it can be accommodated in a suit-case of ordinary dimensions by placing the umbrella diagonally therein as shown in Fig. 1, and the most convenient location for the umbrella is found to be upon the inside of the suit-case top, as also shown in the drawing. 70

Suit-case tops are usually provided with buckled straps 7,8, to hold shirts or other articles of clothing, these straps being arranged transversely of the cover, as shown. My invention provides means for easily and quickly 75 securing the umbrella to these straps. For this purpose I provide two holders, as shown in detail in Figs. 2, 3 and 4. Each holder comprises a loop 10 to receive the umbrella body, a detachable spring-clasp 11 to engage 80 the strap, and an eye 12 to hold the handle, as will be explained. Ordinarily, it would be unnecessary to provide a handle-holding eye on both of the holders, but for the sake of uniformity in manufacture this eye might 85 usually be supplied on both of the holding devices for one suit-case. Where an umbrella is used, which has both a detachable handle and a detachable tip, the eye of one of the holders might be used for the handle 90 and the other for the tip.

In a preferred device, the holding device as shown is made of a single piece of wire. One end of the wire is formed into the eye 12. This is located at the end of a shank 13. 95 At the opposite end of the shank there is a twist 14 to close the loop 10 and hold it properly in relation to the clasp. Adjacent to this twist there is an open coil 15 of one or more turns to provide a spring for the 100 clasp 11. This clasp preferably has an inwardly-curved portion 16 adapted to firmly grasp the strap between said portion and the shank 13 or adjacent parts, as clearly shown in Fig. 2. The free end of the clasp part of 105 the wire is formed into a hook 17 to engage shank 13.

The eye 12 is usually made to fit quite closely the dowel 5 of the handle.

In applying the holders to a suit-case it 110 is unnecessary to unbuckle the straps 7 and 8. The clasps 11 of two of the holding de-

10 vices are opened and one is placed over each strap and secured in the position shown in Fig. 1. The umbrella in folded condition is then easily thrust through the loops 10 and the dowel of handle 3 is thrust through eye 12 until latch 6 snaps in back of the eye and holds the handle securely in position as shown in Figs. 1 and 3. The umbrella may be easily and quickly removed from the holding device and set up for use in an obvious way.

15 The eye 12 may be conveniently used for receiving the handle dowel, as above described, and it may also serve at the same time as a convenient knob for the operation of the clasp 11. But in some cases this eye could be dispensed with and the handle could be inserted in the coil 15. This coil may, therefore, be considered at the same time a 20 spring and a device to receive the handle.

25 The loop 10, as best shown in Fig. 3, may be formed at a greater or less angle to the shank 13 and other parts of the clasp, and this arrangement together with the angular placing of the entire holding device upon the strap permits the holders to be placed at the proper angle to receive the diagonally-arranged umbrella. The security of the umbrella is augmented by the fact that in many 30 cases, in order to bring the loops 10 in line sufficiently, the straps may be twisted somewhat, and the natural tendency of the straps to straighten out and the tendency of the loops to move out of line with each other, causes them to hold the umbrella body more 35 securely, as understood from Fig. 1.

40 In the broader sense, the invention consists in devices connected with the straps of a suit-case to receive and hold a foldable umbrella diagonally therein. In addition, the invention comprises means for holding the detachable handle in proximity to the umbrella. In a more specific form, the invention consists of clasps adapted to be secured upon suit-case straps without unbuckling the latter, with umbrella-holding loops carried by the clasps, and, in addition, in some cases, an eye associated with one of the holding devices to receive the dowel of a 45 detachable handle and hold the same by engagement of the spring-latch of the handle with the eye.

50 The invention also consists in the specific construction and arrangement of parts as shown and described.

55 I claim:—

1. The combination with a suit-case and straps therein, of holding devices connected with the straps to removably secure an umbrella within the suit-case.

60 2. The combination with a suit-case and straps therein, of umbrella-holding loops secured to the straps and adapted to removably secure a foldable umbrella diagonally within the suit-case.

3. The combination with a suit-case and straps therein, of clasps adapted to embrace and firmly engage said straps, and loops carried by the clasps, said clasps and loops being constructed and arranged so that the loops on the respective straps may be placed approximately in line to receive a foldable umbrella and hold it within the suit-case.

4. The combination with a suit-case and straps therein, of holding devices comprising spring-clasps adapted to be placed about said straps and secured thereon, and loops carried by the clasps adapted to removably secure a foldable umbrella diagonally within the suit-case.

5. The combination with a suit-case and straps therein, of holding devices connected with the straps to removably secure an umbrella within the suit-case, and means connected with one of the holding devices for holding a detachable umbrella handle.

6. The combination with a suit-case and straps therein, of umbrella-holding loops secured to the straps and adapted to removably secure a foldable umbrella diagonally within the suit-case, and means connected with one of the holding devices for holding a detachable umbrella handle.

7. The combination with a suit-case and straps therein, of clasps adapted to embrace and firmly engage said straps, loops carried by the clasps, said clasps and loops being constructed and arranged so that the loops on the respective straps may be placed approximately in line to receive a foldable umbrella and hold it within the suit-case, and an eye connected with one of the loops to hold a detachable umbrella handle.

8. The combination with a suit-case and straps therein, of holding devices comprising spring-clasps adapted to be placed about said straps and secured thereon, loops carried by the clasps adapted to removably secure a foldable umbrella diagonally within the suit-case, and an eye connected with one of the holding devices to hold an umbrella handle.

9. The combination with a suit-case and transverse straps in the top thereof, of holding devices applied to said straps, each holding device comprising a clasp to engage the strap, and an umbrella-holding loop carried by the clasp, one of the holding devices being provided with an eye to hold a detachable part of an umbrella.

10. As a new article of manufacture, an umbrella-holding device for suit-cases and the like, comprising a clasp adapted to be engaged with a strap, a loop connected with the clasp and adapted to receive an umbrella-body, and an eye connected with the clasp adapted to receive a detachable part of an umbrella, such as a handle.

11. An umbrella-holding device, consisting of a wire bent to form a shank and a

clasp coöperating with the shank to engage a strap, a loop connected with the shank and clasp by a twisted portion of the wire, and an eye formed in a part of the wire to receive the stem of a detachable part of an umbrella.

5 12. An umbrella-holding device, consisting of a wire bent to form a shank and a

clasp coöperating with the shank to engage a strap, a loop connected with the shank 10 and clasp by a twisted portion of the wire, the loop being arranged at an angle to the shank and clasp, and an eye formed in a part of the wire to receive the stem of a detachable part of an umbrella.

WILLIAM H. BEEHLER.
